UNITED STATES PATENT OFFICE.

JOHN W. DARLEY, JR., OF BALTIMORE, MARYLAND.

REDUCED-LOCKING-STITCH BUTTON-SEWING MACHINE.

1,125,821.

Specification of Letters Patent. Patented Jan. 19, 1915.

Application filed May 28, 1904. Serial No. 210,263.

To all whom it may concern:

Be it known that I, JOHN W. DARLEY, Jr., a citizen of the United States, residing in the city of Baltimore and State of Maryland, have invented certain new and useful Improvements in Reduced-Locking-Stitch Button-Sewing Machines; and I do hereby declare the following to be a full, clear, and exact description of the invention, such as will enable others skilled in the art to which it appertains to make and use the same.

My invention relates to improvements in button sewing machines, and the object of my invention is to produce a machine which will sew a button onto a garment or other fabric by means, whereby the sewing thread does not come through the under surface of the fabric except at one point, thereby rendering the threads on the underside of the fabric almost invisible.

Further objects are to sew a button on a garment or other fabric separated therefrom by a neck of thread, and to wind a thread about said neck of thread, which winding 25 thread may be knotted by hand or by machinery, or secured in any suitable manner.

With these objects in view my invention consists in the construction and combinations of parts as hereinafter described and 30 claimed.

In the accompanying drawings—Figure 1 represents a side elevation of a sewing machine embodying my invention. Fig. 2 is an end view of the needle end thereof. Fig. 3 is a section on the line 3—3 of Fig. 4. Fig. 4 is an enlarged bottom plan view of the blind stitch mechanism. Fig. 5 is a plan view of the same. Fig. 6 is a sectional view of the same on the line 6—6 of Fig. 5. Fig. 7 is a diagrammatic view illustrating the operation of the machine. Fig. 8 is a view partly in section of the button chuck. Fig. 9 is a view showing the button sewed to the fabric as it appears after the operation of my machine is finished. Fig. 10 shows a part of the operating lever and its connections.

In this machine the sewing mechanism, winding mechanism, means for starting and stopping these mechanisms, and the automatic locks and devices for preventing mistakes are substantially the same as those set forth in my Patent No. 747,048, dated December 15, 1903, and a detailed description 55 thereof need not therefore be given.

Referring to Fig. 1, *a* represents the bed

plate, *b* the vertical arm of the goose neck, *c* the horizontal arm thereof, and *d* the end of the horizontal arm. The mechanism to the right of the part *b* in Fig. 1 is substantially the same as that described in my patent above referred to. The needle is driven by a shaft passing through the horizontal arm *c* of the goose neck in the usual manner, and the needle is shifted by means of a link *e* and the ordinary shifting plate *f*. This plate is provided with a curved slot *g*, with an index scale thereon, and the pivot pin *h* of the link *e* is adapted to be shifted along in the slot *g* and fastened in any desired position in the well known manner. The plate *f* is pivotally mounted in a bearing on the goose neck in the usual way. The means for holding the spool of the needle thread and the tension and take up devices are all of the usual type. The plate *f*, however, which governs the motion of the needle also governs the action of the switch mechanism, hereinafter described, in the following way: This plate has a slot *j* provided with an index scale. In the slot *j* is mounted a screw *k* on which is pivoted a link *l*. This link is provided with a slot *m*, so that the pivot pin *h* may be adjusted in the groove *j* as desired. The link *l* as the plate *f* vibrates causes the upright arm *n* of a bell crank lever to vibrate, this lever being mounted on a pin *o* secured in brackets *p* on the bed plate. The horizontal arm *q* of this bell crank lever operates the horizontal arm *r* of another lever which is pivoted on a pin *s* in a bracket *t* extending downward from the bed plate. To the free end of the lever *r* is pivotally connected the link *u*.

The parts *q* and *r* overlap and are slotted as shown at *v*, and through this slot passes a pin *w*. This is in order that the movement in either direction of the arm *q* will cause the movement of the arm *r*. The bell crank lever *n*, *q*, is revolvably mounted on the pin *o* and may be fastened in any desired position in the following manner: The bracket *p* carries a sector *x* provided with a curved surface *y*, and on the arm *q* is a boss 2 which carries a washer overlapping the sector *x* on the outside and the boss comes almost in contact with the sector *x*. A screw 1 is provided by means of which the arm *q* may be clamped to the sector *x* in any desired position.

The button chuck and winding mechanism are carried upon a frame 3, which frame is

provided with two ears 4 and 5, which pass over pins 6 and 7 attached to the horizontal arm of the goose neck and to the bed plate respectively. The frame 3 is therefore free 5 to rise and fall on the pins 6 and 7. This vertical motion is caused by a downward movement of a treadle (not shown) which operates a rod 8, Fig. 2, which rod passes through a hole in a lever plate 9 which is mounted on a short stout stub shaft 10, located in a bearing firmly screwed onto the vertical arm of the goose neck. A spring 11 surrounds said bearing and normally tends to bring the parts to their original position as shown in Figs. 1 and 2, the weight 15 of the frame 3 and the parts attached thereto aiding in this motion. The lever plate 9 is provided with a curved projecting end 12 which is adapted when the rod 8 is pulled 20 down to engage the under face of a projection 13 on the ear 5, Fig. 1, so that a downward movement of the rod 8 will cause an upward movement of the frame 3 and the parts attached thereto. In order to prevent 25 a rotary movement of the frame 3 around the pins 6 and 7, a bracket arm 14 is screwed to the horizontal arm *c* of the goose neck. This projects downward and is provided with a slot 15, through which passes a bolt 30 16, provided with a nut 17.

The slot 15 allows the frame 3 to rise and fall a short distance, but it prevents this frame from swinging backward away from the goose neck around the pivot pins 6 and 7, 35 because the bolt 16 passes into the part 18 of the frame 3. Through the bracket arm 14 passes another bolt 19, provided with a nut 20. This bolt reaches over to the part 18, but does not enter it, so that the two bolts 40 and nuts just referred to, prevent the rotary motion of the frame 3, but do not prevent the up and down motion of said frame. The nuts on these bolts are made adjustable, so that the button chuck may be adjusted with 45 reference to the needle, so that it may pass through the holes in the button and so that if it is desired to sew on a four hole button, the button holding chuck may be shifted at the middle of the sewing operation, as described in my Patent No. 747,048, but this button shifting mechanism is not shown in 50 the present drawing.

After a button has been completely sewed on, and it is desired to move the fabric in 55 position for a new button to be sewed on, it is necessary to open the button chuck, so that the new button may be placed therein, and to open the tension of the sewing thread so that the garment or other fabric may be 60 pulled along. These two results are accomplished by the downward movement of the rod 8 under the influence of the treadle.

The frame 3 carries an extension 21, Fig. 2, in which is fixed a rod 22 extending upwardly, and provided with a bent end which

engages in the slot 23 in the horizontal arm 24 of a bell crank lever, which is pivoted on a screw 25 secured in the end *d* of the goose neck. The vertical arm 26 of this bell crank lever is brought down to a knife edge 27. The upward movement of the frame 3, carrying with it the rod 22, swings this knife edge between the plates 28 of the tension device, Fig. 1, throwing them apart and releasing the needle thread from its tension. 75

In sewing on buttons by machinery, each stitch is pulled tight by the takeup and by the action of the succeeding stitch. To insure that the last loop of thread shall be pulled equally tight, I have provided an auxiliary device independent of the ordinary takeup device, which pulls this last loop up with a sharp jerk. This device consists of a curved arm 29 provided with an enlarged perforated end 30 through which the needle thread passes. The arm 29 is firmly secured to a rod 31 passing nearly the full length of the machine. This rod 31 is journaled at one end in a bracket 32 attached to the goose neck, and at the other end in an upright standard 33. At its right hand end, this rod carries a downwardly projecting arm 34 which is adapted to be struck by the rod 35. This rod at the end of the operation of the sewing mechanism 95 rises quickly, giving a sharp upward jerk to the arm 34, which gives a similar jerk to the arm 29, thus drawing the last loop of the needle thread tight, inasmuch as the end 30 of the arm 29 is located between the tension device for the needle thread and the needle. 100

The button chuck performs similar functions to those of the button chuck in my former patent above referred to, and is shown on an enlarged scale in Fig. 8. It consists of adjustable jaws 36 and 37, terminating in hooks 38 and 39, which close around the lower edge of the button. These jaws are mounted upon a screw 40, provided with right and left handed screw threads and having a milled head 41. By turning this head, these jaws are caused to approach toward or recede from each other at a uniform rate, this adjustment being provided 110 in order that the machine may be used for sewing on buttons of various sizes. The button chuck is also provided with an adjustable rear jaw 42, see Fig. 2, so arranged that as the jaws 36 and 37 are adjusted toward each other, the jaw 42 will also be adjusted an equal distance toward the center of a line connecting the jaws 36 and 37, such an adjustment being set forth in my patent above referred to. The chuck, however, is provided with a fourth jaw 43, Fig. 1, which is adapted to be swung aside as the frame 3 is lifted at the end of the operation of sewing on a button, so that a new button may be placed in the chuck. This lifting operation 125

as described is caused by the downward movement of the rod 8, and this movement also swings aside the movable jaw 43 by any suitable means, such as those set forth, for example, in my prior patent already referred to, or by means of the following connections: In a slot in the lever plate 9 is mounted the end 44 of a lever, provided with an arm 45 and an arm 46, said lever being pivoted on a shouldered pin 47 passing through an extension 48 of the frame 3. A nut 49 retains said pin in position. The movable jaw 43 of the button chuck is firmly attached to a rod 50 passing through the bearing 51 and having attached to it the shoulder 52, to which is attached a crank 53. A link 54 connects this crank with the end of the arm 46 of the lever already referred to. A downward motion of the rod 8, therefore, causes the movable jaw of the button chuck to swing forward, thereby opening said chuck, so that a new button may be placed therein.

In Fig. 8, 55 represents the plate from which the button chuck is supported. This plate is provided with a downwardly projecting cylindrical extension 56, which is bored out as shown in 57. Within this hollow extension 56 slides a sleeve 58 which fits in said extension rather closely. The extension is also provided with a slot 59 through which passes a screw 60, and a washer 61 curved to fit around the curved surface of the extension 56 is interposed between the head of said screw and the extension 56. This screw passes through said washer, through the slot 59, and into the cylinder 58, so that said cylinder may be adjusted as desired up and down in the extension 56. Preferably a scale is cut upon one face of the cylindrical extension 56, and the lower edge of the washer 61 acts as a point for said scale. The cylinder 58 is hollow, and through it passes a rod 62 which supports the button chuck. This rod passes freely through the cylinder 58, and a pin 63 prevents it from falling through said cylinder, or instead of a pin, the upper end of the rod may be provided with an enlarged head, both of these constructions being shown in Fig. 8. The button chuck, therefore, is free to rise and fall a limited distance, its supporting rod passing freely through the cylinder 58. The lower part of the rod 62 is expanded, forming a shoulder 65 which fits closely within the round hole 57. Between this shoulder and the cylinder 58 is coiled a spring 64 which tends to keep the button chuck in its lowest possible position, while permitting it to rise upwardly against the tension of said spring. The cylindrical part 65 is firmly fixed to the cross piece 66 of the button chuck frame, which includes two side pieces 67 and 68 and an inner cross piece 69. The upper ends of the side pieces

67 and 68 are slotted as shown in dotted lines in Fig. 8, and in full lines at 70 in Fig. 2, and in these slots plays freely a horizontal bar 71 which is attached to or made integral with the cylindrical extension 56, 70 which construction keeps the button chuck and the supporting plate 55 from swinging relatively to each other.

The ear 5 of the frame 3 when said frame is in its lowest position rests solidly on a shoulder on the pin 7, which limits the downward movement of said frame 3, thereby limiting the approach of the button chuck toward the fabric. The distance between the bottom of the button and the fabric is determined by the position of the sleeve 58 which is adjustably secured in its support by means of the screw 60, while at the same time the button chuck is free to rise a limited distance against the tension 85 of the spring 64, which always tends to restore it to the position shown in Fig. 8.

On the main frame *a* is mounted a bed plate 72, the main portion of which terminates at the point 73, but is provided with 90 projecting arms 74 and 75 which form supports for the operating parts of the shuttle. Through the parts 74 and 75 a hollow tube 76 is driven which fits said supports by what is ordinarily called a driving fit. On the 95 tube 76 is mounted the upper bearing portion or sleeve 77 of a link 78, and this sleeve is prevented from sliding longitudinally on the tube 76 by the arms 74 and 75. The link 78 is provided with a curved lever 79 to 100 which the link *u* is pivoted by the pin 80, so that the movement of the lever *r* will cause the movement of the lever 79, and therefore will effect a lateral swing of the link 78. The lower part of this link is provided with a split bearing 81, provided with ears 82, 83, united by belts 84. Within the bearing 81 is revolvably mounted the sleeve 85. The sleeve 85 is provided on its rearward end with an upward extension 86, expanded at the top as shown at 87-87, Fig. 3. These lateral extensions have two vertical extensions 88-88, which fit closely around the circular portion 89, which is formed integral with the bearing end of the 115 arm 75, but it will be noted by reference to Fig. 3, that the center of the circular portion 89 is somewhat above the center of oscillation of the link 78. The purpose of this will be hereinafter described. The front 120 portion of this sleeve 85 extends upwardly as shown at 90 in Figs. 4 and 6, but extends laterally as shown at 91-91 in Fig. 4, and forwardly as shown at 92-92 in said figure.

To the vertical extension 90 is screwed the shuttle case 93, which is of ordinary construction, except that it is cut away as shown at 94 in Fig. 1 in order to provide clearance for the shaft 95 when swinging past said 130

shaft. The vertical extension 90 passes beyond the forward extensions 92 and terminates in a curved upper portion 96, Fig. 6. To this curved upper portion 96, the flat portion of the extensions 87—87, 91—91 and the curved upper portions of the extensions 88—88, is screwed a shield 97, designed to prevent the fabric from getting into the working parts. This shield 97 is provided with slots 98—98, Fig. 5, to permit of free movement of the same past the supports 74 and 75.

To the extensions 92—92 is screwed the throat plate 99, which is at its central portion bent up as shown at 100 in Fig. 1, making a corresponding bend in the fabric 101, to which the button is to be sewed. Above the throat plate 99 and substantially parallel thereto, is a clamp 102, mounted in ears 103 carried by the throat plate, and a spring 104 is coiled around the pin which supports this clamp and normally forces the same down against the top of the fabric. The clamp 102 is cut away as shown at 105 for the passage of the needle and to permit a sufficient clearance for the button to come in contact with the cloth. The clamp 102 is also provided with a projecting portion 106, beneath which a swinging lever 107 is adapted to pass; lifting the clamp in order that the work may be introduced between the throat plate and clamp, or withdrawn therefrom. As long as the lever 107 is turned into its vertical position, the clamp 102 is held up, because the spring 104 presses the clamp down on the lever 107 and prevents it falling back to its original position. As soon, however, as the lever 107 is withdrawn by hand, the spring 104 brings the clamp down into position upon the fabric, as shown in Fig. 1.

Inside the shuttle case 93 is revolvably mounted the ordinary hook and shuttle carried on the end of the shaft 108, which is revolvably mounted in the sleeve 85. On the rear end of the shaft 108, is mounted a gear wheel 109, which gear wheel meshes with the pinion 110 on the shaft 111, which passes through the tube or sleeve 76. The inner end of the pinion 110 bears against the end of the sleeve 76, and the outer end of the shaft 111 is provided with an enlargement 112, which construction prevents the lateral motion of the shaft 111 and the pinion carried thereby. The sleeve 77 being connected with the sleeve 81 by the link 78, it is obvious that no matter how much the shaft 108 is oscillated laterally, the gear wheel 109 and pinion 110 will always remain in operative relation with each other. With the pinion 110 meshes the large driving wheel 113 which is protected by a casing 114 to keep the fabric from catching in the gears. This casing 114 extends out to the end of the machine as shown at 115, Fig. 1,

but is cut away as shown in Fig. 6 to afford a sufficient space for the swinging of the pinions and gears, more especially the gear wheel 109. The forward end of the plate 72 is slotted as shown at 116 to afford the proper clearance for the shuttle case 93 as the latter is swung back and forth.

The gear wheel 113 is mounted on the shaft 95, Figs. 1 and 4, which is shouldered as shown at 117, Fig. 4, and on which is mounted a bevel gear wheel 118 which meshes with a similar gear wheel 119, carried by the main driving shaft 120 of the machine, which by its revolution drives the shuttle in the proper direction by means of the gearing already described.

The operation is as follows: The button chuck is adjusted at the proper height in its support 56 to make the required length of neck of thread. The operator places his foot upon the treadle, the lever 9 then lifts the frame 3 and opens the button chuck, allowing a button to be placed therein. Then the lever or catch 107 is moved under the projection 106 lifting the clamp 102, whereupon the fabric is slipped over the throat plate, the treadle released and the lever 107 pulled out, whereupon the parts return to the position shown in Fig. 1 with the button held fast in the chuck. The sewing mechanism is then started in operation by pulling down the rod 127 by means of the right hand treadle, as described in my former patent already referred to. Then the sewing mechanism performs its work, and cannot be tampered with by the operator until the sewing and winding operations are finished. During the sewing operation, however, the frame carrying the shuttle is tipped alternately from side to side, as shown diagrammatically in Fig. 7, the result being that the needle enters the fabric at an angle thereto, this angle depending upon the space through which the shuttle carrying frame is tilted. The plate *f* having two index scales thereon, as already described, the links *e* and *l* should be adjusted in such a way that the tilting of the shuttle frame will always be exactly proportional to the vibration of the needle carrying frame, so that the needle will exactly pass through the holes of the button and through the fabric at the desired angle in every case to cause the needle to pass through but one point on the bottom of the fabric when a two-hole button is used, or through two points when a four-hole button is used. The vibration of the frame carrying shuttle is caused, as already described, by the movement of the bell crank lever 125 *n*, *q*, which causes the vibration of the lever *r* and the vibration of the link *w*, thus causing the shuttle frame to vibrate, as is shown in Fig. 7, in which the full lines represent

the parts as shown in horizontal position, 126

as in Fig. 1, and in which the dotted lines represent the position assumed while a stitch is being made through the left hand hole of the button, the needle always passing at about the center point through the top surface of the upwardly projecting portion of the throat plate. The clamp 102 forming a part of the presser plate is cut away sufficiently so that the button can always rest on the top of the fabric when a stitch is being formed, and if the fabric is thick the button chuck will yield upwardly against the tension of the spring 64.

It is necessary, in vibrating the shuttle frame, to allow it to rise slightly as it is swung to one side, because the takeup device is always arranged to take up the excess of thread while the throat plate is in the horizontal position. Owing to the arrangement about to be explained, a greater length of thread to form the neck is never needed in the angular positions than is needed in the horizontal position, and usually a less length is needed. This provision for allowing the shuttle frame to rise, when it is swung to one side of the position shown in Fig. 1, is accomplished as follows: 121 represents the center around which the link 78 vibrates, while 122 represents the center of the stationary part 89, and in this part 89 is loosely embraced by the forks 88, 88; of the extension 87, the result being that when the link 78 is vibrated, it vibrates around the center 121, but the line connecting the center of the lower sleeve of the link 78 with the center of movement 121 does not always pass through the center 122.

Representing by 123 the center of the lower sleeve of the link 78, the center 122, the center of the upper part of the throat plate, and the center 123 are always in a straight line, and when the throat plate is in a horizontal position, the center 121 is also in this line, but when the parts are tilted, as shown in dotted lines in Fig. 7, the center 121 is not in the line connecting the centers 122 and 123. This allows the throat plate to approach the button, and so provides for a loosening of the stitches of the needle thread which have been passed through the button.

In Fig. 7, 124 represents the well known shuttle hook, and when the shuttle frame and throat plate are in the position shown in dotted lines in said figure, this hook is shown as having its point on the dotted line 125, which is the line of motion of the needle when the parts are as shown in dotted lines in said figure. While the shuttle frame and throat plate are swinging from the position shown in dotted lines in Fig. 7 to the reverse position, in other words, until the center 123 has moved an equal distance to the left of its normal position, shown in full lines in said figure, it is obvious that the

ratio of the drive of the gear wheel 109 by the pinion 110 would be interfered with, inasmuch as they change their positions relatively to each other. It is necessary, during this vibration, that the shuttle hook 124 should be brought back so that its point shall be in line with the dotted line 126 which is the line of motion of the needle when the shuttle is swung to the left, assuming that the machine has stopped for an instant while the shifting operation takes place. As a matter of fact the shuttle and shuttle hook continually revolve. The pinion 110 and gear wheel 109 are therefore so proportioned relatively to each other that by the time the shifting operation has taken place the point of the shuttle hook 124 will be just on the dotted line 126 at the proper time with reference to the movement of the needle, and will thus have the same relation relatively to said needle as existed when the first stitch was made. The sewing after this is merely a repetition of what has already been described. Furthermore, the gear wheels 118, 119, 113 are so proportioned with reference to each other, to the pinion 110 and gear wheel 109 that one revolution of the driving shaft causes exactly one revolution of the shuttle shaft as is usual in ordinary sewing machines.

After the button has been sewed on a thread may be wrapped around the neck of thread connecting the button with the fabric as described in my former patent, and this thread may be knotted by hand or by machinery. The mechanism for performing this winding is shown in Figs. 1 and 2, but it has not been described as it is substantially the same as that set forth in my former patent.

A two hole button or a four hole button can be used, as described in my patent above referred to, and mechanism may be used for tying a knot in the winding thread and for trimming the same, but to avoid complication in the illustration of the machine, these parts have not been shown or described in full. By the machine set forth in this application I sew the button on in contact with the cloth, and then separate the fabric from the button to form a neck of thread, which is always a necessary feature in a successful button sewing machine.

In Fig. 9 is shown a fabric in cross section with a button sewed on to the same as it would appear when sewed on by my machine, that is to say with the sewing threads passing through the fabric at an angle thereto and coming to a point, the button being separated from the fabric by a neck of thread, a winding thread being wrapped around said neck of thread and having its ends knotted together.

While I have thus described my invention, I wish it to be distinctly understood

- that I do not limit myself to the exact details shown and described as these might be varied greatly without departing from the principle of my invention, the main feature of which is that the sewing threads do not pass through the fabric parallel to each other, but at an angle to each other, thereby practically concealing said threads on the inner side.
10. I desire by this application to cover broadly a button sewing machine which will reduce the appearance of the thread on the underside of the fabric, whereas in ordinary button sewing machines in which the stitches are parallel to each other quite a large amount of thread appears on the underside of the fabric, which is objectionable in fine work.
- I claim:
20. 1. In a button sewing machine, the combination of a needle, means for causing said needle to reciprocate and to vibrate, movable devices for holding the fabric, and means for tilting said devices in time with the vibrations of said needle, thereby causing the stitches in the fabric to assume a pyramidal form, substantially as described.
2. In a button sewing machine, the combination of a needle, means for reciprocating and vibrating said needle to parallel vertical positions, movable devices for holding the fabric, and means for tilting said devices alternately back and forth, about an axis so located with respect to the needle that it is caused to pass diagonally through the fabric and through one hole on the underside thereof while passing through two or more holes in the button, substantially as described.
30. 3. In a button sewing machine, the combination of a needle, means for reciprocating and vibrating said needle to parallel vertical positions, movable devices for holding the fabric, and means for tilting said devices back and forth, about an axis so located with respect to the needle that the stitches assume a triangular or pyramidal form in the fabric, substantially as described.
40. 4. In a button sewing machine, the combination of a needle, means for reciprocating and vibrating said needle, movable devices for holding the fabric, means for tilting said devices back and forth about an axis so located with respect to the needle that the stitches assume a pyramidal form in the fabric, and a common operating means for said needle and said fabric-holding devices, substantially as described.
50. 5. In a button sewing machine, the combination of a yielding button chuck, and means for intermittently pressing a fabric against a button held in said chuck, substantially as described.
60. 6. In a button sewing machine, the combination of a button chuck, a support in which said button chuck is movably mounted, said support being provided with a stop which limits the downward movement of the said chuck and a spring against whose tension said chuck may be moved upwardly, substantially as described.

7. In a button sewing machine, the combination of a button chuck, a support in which said button chuck is movably mounted, said support being provided with a stop which limits the downward movement of the said chuck and a spring against whose tension said chuck may be moved upwardly, substantially as described.

8. In a button sewing machine, the combination of a button chuck, a support provided with a cylindrical bore therein, a cylindrical stop slidably mounted in said bore, means for adjusting and securing said stop in said bore, said button chuck being provided with a stem passing through said stop and with devices for preventing said stem from falling through said stop, and a spring between said stop and the main part of said button chuck, substantially as described.

9. In a button sewing machine, the combination of sewing mechanism including a vibrating and reciprocating needle, work holding mechanism, means for tilting said work holding mechanism back and forth in unison with the motions of said needle, means for holding a button in contact with the fabric during the sewing operation, and means for separating the button from the fabric to form a neck of thread after the sewing operation, substantially as described.

10. In a button sewing machine, the combination of sewing mechanism, means for holding the button in contact with the fabric while the stitch is being made, means for separating said fabric from said button, and means for taking up the sewing thread while said fabric is separated from said button, substantially as described.

11. In a button sewing machine, the combination of a reciprocating and vibrating needle work holding means, button holding means, means for tilting said work holding means and causing it to simultaneously approach said button holding means, and operating devices for the above-mentioned parts, substantially as described.

12. In a button sewing machine, the combination of button holding means, stitch forming mechanism, a work holding device, and means for tilting said work holding device back and forth, thereby causing the fabric to approach the button while the

stitch is being made, and then to recede from said button, substantially as described.

13. In a button sewing machine, the combination of sewing mechanism, including a needle, operating means for said needle, work holding devices, means for tilting said work holding devices in unison with the movements of said needle, whereby the needle thread is caused to pass diagonally through said fabric in directions inclined to each other, a take-up device, and separate means for drawing the last loop in the needle thread tight, substantially as described.

14. In a button sewing machine, the combination of button holding means, a vibrating needle, work holding devices, and means for tilting the work holding devices relatively to said button holding means, substantially as described.

15. In a button sewing machine, the combination of button supporting means, work holding devices, a vibrating needle, automatic means for tilting the work holding devices during the sewing operation and button shifting means, whereby a four hole button may be used, substantially as described.

16. In a button sewing machine, the combination of button holding means, work holding devices coöoperating to clamp both sides of the work and means for tilting the work holding devices, substantially as described.

17. In a button sewing machine, the combination of button holding means, work holding devices adapted to form a ridge in the work, and means for tilting the work holding means transversely to the path of the needle, substantially as described.

18. In a button sewing machine, the combination of means for holding a flat pierced button having a plurality of holes, work holding means, a needle carrying a thread, and means for passing said thread in succession through each of the holes in the button at right angles thereto and diagonally through the work, substantially as described.

In testimony whereof, I affix my signature, in presence of two witnesses.

JOHN W. DARLEY, JR.

Witnesses:

ADOLPH MILLER,
M. COHN.
